Claims priority, application Great Britain June 12, 1956
3 Claims. (Cl. 210—130)

This invention relates to filters for liquids and in particular to oil filters for internal combustion engines.

In order to secure an oil filter to an internal combustion engine in communication with oil inlet and outlet connections thereon, it has been proposed to incorporate in the filter casing a filter head adapted to be bolted to a mounting face on the engine so that oil inlet and outlet passages in the filter head are in communication with corresponding inlet and outlet passages in the mounting face. It is usual to embody in the head a relief valve to permit direct flow between the oil inlet and outlet passages on the engine mounting face, bypassing the oil filter, when the filter element becomes clogged with accumulated impurities.

According to the present invention the construction of an oil filter is simplified and its cost of manufacture reduced by dispensing with a head and mounting face of the kind referred to above; instead, a groove is machined in the engine mounting face so that the filter can be secured direct to the mounting face, preferably by a single central bolt, with the end edge of the filter casing seated in the groove (a seal ring preferably being interposed) and with the inlet and outlet passages in the filter in communication with corresponding passages in the mounting face.

In order that the relief valve for the filter can be positioned in such a way that it will not, when in operation, involve the entrainment of impurities in the direct flow of oil between the oil inlet and outlet, the relief valve is, according to a particular feature of the invention, formed as an assembly conveniently a casting, comprising a valve chamber with a ball valve therein, which is adapted to be mounted adjacent the filter element and about the central bolt by which the filter element and casing are secured on the engine mounting face.

According to a further feature of the invention, the valve is constructed so that it is a free fit on the said bolt and, when the filter is mounted horizontally, automatically assumes a position in which the inlet to the valve will be above the level at which impurities will accumulate in the filter casing.

According to another feature of the invention, the relief valve assembly is adapted to be located in a fixed position on the engine mounting face. This may be achieved by arranging the assembly so that it can be bolted to the mounting face, or secured thereto by means of interengagable spigot and socket formations on the mounting face and the valve housing.

The scope of the invention is defined by the appended claims; and how it can be performed is hereinafter particularly described with reference to the accompanying drawings, in which:

FIGURE 1 is a sectional elevation of a filter according to one embodiment;

FIGURE 2 is a plan of FIGURE 1;

FIGURE 3 is a sectional elevation of an engine mounting face for use with the filter shown in FIGURES 1 and 2;

FIGURE 4 is a modification of the relief valve shown in FIGURES 1 and 2;

FIGURE 5 is a modification of the engine mounting face shown in FIGURE 3, for use with the relief valve of FIGURE 4;

2

FIGURE 6 is a further modification of the relief valve shown in FIGURES 1 and 2;

FIGURE 7 is a further modification of the engine mounting face shown in FIGURE 3, for use with the relief valve of FIGURE 6;

FIGURE 8 is a modification of the filter shown in FIGURE 1;

FIGURE 9 is a further modified form of engine mounting face for use with the filter of FIGURE 8;

FIGURE 10 is an elevation of the relief valve shown in FIGURE 8;

FIGURE 11 is a plan of FIGURE 10;

FIGURE 12 is a section on the line XII—XII of FIGURE 11;

FIGURE 13 is a section on the line XIII—XIII of FIGURE 11; and

FIGURE 14 is a section on the line XIV—XIV of FIGURE 12.

In the different figures of the drawings parts which are substantially similar and are intended to carry out similar functions bear similar reference numerals.

In carrying the invention into effect according to one embodiment thereof, shown in FIGURES 1 to 3 a filter element 1 enclosed in a metal casing 2 is arranged to be

secured to an engine mounting face 3 by means of a central bolt 4 which extends coaxially through the filter casing 2 and a central outlet passage 5 of the filter element 1 and when screwed into a tapped hole 6 in the mounting face 3 draws the end edge 7 of the filter casing 2 into sealing engagement with an annular groove 8 machined in the mounting face 3, in which latter are also formed oil inlet and outlet passage 9, 10 in communication with the engine lubrication system. The oil inlet opening 9 is coaxial with the tapped hole 6. A hollow

portion 11 of the mounting bolt 4 has openings 12 in the wall thereof in communication with the central outlet passage 5 of the filter element 1, to allow filtered oil to flow through the openings 12, the hollow portion 11 of the bolt and into the oil inlet passage 9.

The filter element 1 is mounted with its axis in a horizontal plane and a relief valve 14 to provide a by-pass flow of oil when the filter is clogged is made as a metal casting 15 within which is a substantially cylindrical valve chamber 16 embodying a valve seat 17 closable by a ball

18 under the action of a spring 19. The valve chamber 16 has an inlet opening 20 on one side of said valve seat 17 and an outlet opening 21 which communicates with a recess 22 at one end of the casting, one end of said recess 22 which extends at right angles opening into the outlet passage 5 of the filter element 1 and the other end opening into a co-axial bore 23 which extends at right angles to the axis of the valve chamber 16. This bore 23 is made of such dimensions that the relief valve 14 will fit freely about the bolt 4 by which the filter element 1 and casing 2 are secured to the engine mounting face 3. Thus, when the relief valve 14 is placed on the securing bolt 4 it can rotate freely thereon and its

55 centre of gravity is so placed that the relief valve 14 will assume a position in which the inlet 20 to the valve chamber 16 therein is above the horizontal plane which includes the axis of the bolt 4. In other words, the valve inlet and the center of gravity of the relief valve assembly are on opposite sides of a plane in which lies the axis of the bolt 4. A spring 24 bears at one end against the

60 closed end 25 of the filter casing 2 and at its other end against a sealing plate 26 which seals the other end of the filter element 1; and the bolt 4 extends through a central opening in the sealing plate 26, in which it is a close fit. When the bolt 4 is tightened up the spring 24

65 is compressed to force opposed faces 27, 28 on the relief valve 14 respectively into sealing contact with the engine mounting face 3 and with the oil outlet passage 5 at one

end of the filter. The headed end of the bolt 4 carries a collar 29 within which is a sealing ring 30 which seals the opening in the end wall 25 of the casing 2 through which the bolt 4 passes.

A sealing gasket 13 is preferably interposed between the end edge 7 of the casing 2 and the annular groove 8.

When the filter element 1 becomes clogged the relief valve 14 comes into operation to provide direct flow of oil between the inlet and outlet passage 9 and 10 in the mounting face 3 so as to bypass the filter. As the inlet 26 to the relief valve 14 lies above the central horizontal axis of the filter it will be above the level at which impurities removed from the oil will tend to accumulate within the filter casing 2.

In a modified form of the arrangement described above, shown in FIGURES 4 and 5, the engine mounting face 3 is provided with tapped holes 31 adapted to receive screws (not shown) located in screw holes 32 in lugs 33 on the relief valve 14, whereby the latter can be secured in the required position on the mounting face 3 so that the inlet 29 of the relief valve 14 will, as before lie above the level at which impurities accumulate in the filter casing 2.

In a further modification of this arrangement, shown in FIGURES 6 and 7, the relief valve 14 and the mounting face 3 are formed with co-operating spigot and socket formations 34, 35 respectively, arranged so as to locate the relief valve 14 with the inlet thereto in the desired position above the level of impurities collected in the filter casing 2.

Where the filter is mounted on the engine in a position such that it extends vertically above the mounting face 3, the impurities removed during filtration will settle under gravity at the base of the casing 2 adjacent the mounting face 3 and in this case, as shown in FIGURES 8 and 9, the relief valve assembly 14 is mounted on the bolt at the end thereof remote from the mounting face 3. In this case the filter element 1 abuts the engine mounting face 3 with the filter element outlet 5 in communication with an inlet passage 37 in the mounting face spaced from the tapped hole 6 which receives a central mounting bolt 38 which is not made hollow; a helical spring 39 mounted on the bolt 38 at the end remote from the mounting face 3 abuts the end face 27 of the relief valve 14 to urge the opposite end face 28 thereof into sealing contact with the adjacent end of the central outlet passage 5 of the filter element 1.

It is preferred in any of the forms of the invention described above to employ a valve assembly 14 in which the interior of the valve chamber 16 is constructed so that when the valve ball 18 is unseated the flow of oil through the valve chamber 16 diverts the ball into contact with the wall at one side only of the chamber 16 and thereby reduces chatter caused by oscillation of the ball 18 between opposed walls of the valve chamber. Such an arrangement also effects a reduction in the resistance to flow provided by the valve.

Accordingly, as best shown in FIGURES 10 to 14, the relief valve 14 has a valve chamber 16 with a recess 49 which extends axially thereof and over a substantially 90° segment of the substantially cylindrical wall of the chamber 16. Thus, when the valve ball 18 is forced off its seat 17 the liquid passing the valve will tend to flow towards the opening 21 by way of the recess 49 only, and thus tend to force the ball 18 into contact with a substantially diametrically opposite portion of the cylindrical wall of the chamber 16.

The valves 14 shown in FIGURES 10 to 14, FIGURE 6, and in FIGURES 1 and 2 are essentially of the same construction and differ in detail only, as will be readily understood from a consideration of the foregoing description thereof, and of the drawings.

I claim:

1. A filter unit comprising a casing with an open end, a bolt extending through said casing with a threaded end in said casing open end for attaching the unit to an engine block, an annular filter element and a relief valve assembly rotatably and slidably mounted within said casing on said bolt, said casing and filter element defining a first chamber between them for receiving contaminated fluid, said filter element and bolt defining an outlet chamber for clarified fluid, a spring encircling said bolt and positioned to urge said filter element and relief valve assembly toward said casing open end, said relief valve assembly having a pressure actuated one way valve and a bypass passage with an inlet at one side only of said bolt and an outlet leading to said outlet chamber, and the said inlet and the center of gravity of said relief valve assembly being on opposite sides of a plane in which lies the axis of said bolt.

2. A filter unit comprising a cup-like casing with an open end, a bolt with a portion extending within said open end and adapted to hold said unit with its open end in sealed relation with an engine block, said bolt portion having a discharge passage leading from said casing, a filter element within said casing and surrounding said bolt, a port in said bolt connecting the interior of said filter element with said discharge passage, a relief valve assembly rotatably arranged on said bolt and engaging one end of said filter element in sealed relation, a pressure-actuated relief valve, inlet and outlet ports in said assembly and controlled by said valve, said inlet port communicating with said casing outside said filter element, said outlet port communicating with said bolt portion discharge passage, and the said inlet port and the center of gravity of said relief valve assembly being on opposite sides of a plane in which the axis of said bolt lies whereby the said inlet port will assume a position above an impurities settlement zone within said casing when said unit is mounted on said block with the said bolt inclined to the vertical.

3. A filter unit comprising a casing having a fluid inlet end and a fluid receiving chamber, a filter element in said chamber, a bolt extending into said casing and adapted to support said inlet end on an engine, a discharge passage in said bolt having one end near the plane of said fluid inlet end, said passage also communicating with the interior of said filter element, a relief valve assembly surrounding said bolt and arranged freely rotatable with relation thereto by the action of gravity during mounting, a passage in said relief valve assembly having an inlet in communication with said fluid receiving chamber outside said filter element and an outlet in communication with said discharge passage of said bolt, a pressure-actuated one-way valve controlling flow through said relief valve assembly passage to said discharge passage, and the said inlet and the center of gravity of said relief valve assembly being on opposite sides of a plane in which lies the axis of said bolt.
